CLAIM

(22) Filed: **May 2, 2012**

The ornamental design for a housing for a force sensor that measures the weight of vehicles that pass the sensor on the road, as shown and described.

(30) **Foreign Application Priority Data**

DESCRIPTION

Jul. 11, 2011 (CN) 2011 3 0410764

FIG. 1 is an elevated perspective view of an embodiment of the ornamental design for a housing for a force sensor that measures the weight of vehicles that pass the sensor on the road;

(51) **LOC (9) Cl.** **08-05**

FIG. 2 is an enlarged perspective view of the front or the back portion of the housing of FIG. 1;

(52) **U.S. Cl.**

FIG. 3 is a top plan view of the housing of FIG. 1 with the redundant middle portion omitted;

(58) **Field of Classification Search**

FIG. 4 is a bottom plan view of the housing of FIG. 1 with the redundant middle portion omitted;

USPC D10/87, 94, 95; D25/119-125; 52/301;
73/1.13; 177/132-136, 139, 200, 246;
256/65.01, 65.02, 65.11, 65.14; 340/666;
702/101, 173-175

FIG. 5 is a plan view of the front of the housing of FIG. 1, the back view being identical thereof;

See application file for complete search history.

FIG. 6 is a plan view of the left side of the housing of FIG. 1 with the redundant middle portion omitted; and,

(56) **References Cited**

FIG. 7 is a plan view of the right side of FIG. 1 with the redundant middle portion omitted.
